UNITED STATES PATENT OFFICE.

OSCAR L. BARTLETT, OF MOUND CITY, ILLINOIS.

HAMPER-FORMING DEVICE.

Application filed February 7, 1927. Serial No. 166,543.

This invention relates to improvements in hamper forming devices and is an improvement over my U. S. Letters-Patent #1,600,920, granted me September 21st, 1926.

5 The primary object of the invention is to simplify the forming of the hamper and for maintaining the same in a temporarily assembled position for insertion into the usual stapling or stitching machine.

10 Another object of the invention is to provide a frame into which the hoops are inserted and held in suitable spaced relation, after which the staves are dropped in and automatically spaced, and which staves and 15 hoops are held in position by the action of truss hoops which are dropped into the hamper for temporarily holding the parts in position until securely fastened together after which time the truss hoops are removed 20 for further use.

With these and other objects in view, the invention resides in certain novel construction and combination and arrangement of parts, the essential features of which are 25 hereinafter fully described, are particularly pointed out in the appended claim, and are illustrated in the accompanying drawing, in which:—

Figure 1 is a perspective view of my improved hamper forming device, showing a hamper in a set-up position.

Figure 2 is a top plan view of the same.

Figure 3 is a vertical sectional view therethrough.

35 Referring more particularly to the drawing, the reference numeral 10 designates my improved hamper form in its entirety and which comprises a base 11 having equidistantly spaced post 12 rising therefrom in circular formation and which converge 40 toward the base 11, the degree of convergence depending upon the shape of the hamper to be formed. The posts 12 are joined at their tops by a ring 13 on which radially arranged spacer members 14 are mounted. The members 14 are hingedly mounted on 45 the top of the ring as at 14' so that they may be swung inward to an open position to space the staves at the top or swung outward to an inoperative position. The inner 50 faces of the posts 12 are provided with horizontally aligned shoulders 15, which are suitably spaced for supporting outer hoops of the hamper during the assembling operation.

In practice, an operator first places the

bottom B of the hamper upon the base 11 together with the lower outer hoop O. The intermediate outer hoops H are then placed upon the respective horizontally aligned shoulders and are supported in position thereon while the uppermost hoop U rests upon the top ring 13. The staves S are next dropped into place and are held in spaced relation by the spacer members 14. 60 In the formation of certain type of hampers, this is, when the staves come together, the spacer members 14 are swung outward to an inoperative position.

65 Truss hoops T are next inserted and are of different sizes. Two truss hoops are all that is necessary in the construction of an ordinary size hamper, there being one hoop inserted to a point adjacent the bottom of the hamper, and a larger truss hoop inserted 70 adjacent the top of the hamper, whereupon the said truss hoops are wedged into tight engagement with the staves S, which staves are in turn expanded against the outer hoops. The hamper may now be lifted 75 from the form in a temporarily set-up position for insertion into the stapling or stitching machine, after which the inner truss hoops T are removed for use in the construction of another hamper.

80 From the foregoing description, it will be appreciated that any one unskilled in the art of hamper construction may set up a hamper in quick time and with little effort on his part, as it is only necessary to drop the hoops and staves into their positions and 85 insert the truss hoops to cause the parts to frictionally engage.

90 While I have described what I deem to be the most desirable embodiment of my invention, it is obvious that many of the details may be varied without in any way departing from the spirit of my invention, and I therefore do not limit myself to the exact details of construction herein set forth nor 95 to anything less than the whole of my invention limited only by the appended claim.

100 What is claimed as new is:—

105 A hamper form comprising a base adapted to receive the bottom of the hamper to be formed and the lower outer hoop therefor, a frame structure supported upon said base embodying a plurality of posts arranged in converging relation and rising from said base and a ring fixedly supported upon the 110 tops of said posts, the staves of the hamper to be formed adapted to have their lower

ends resting upon said base and their top ends against said ring to temporarily support them in converging relation, pointed spacer members supported by said ring and 5 extending inwardly therefrom for spacing the top ends of the staves, and shoulders provided on the inner sides of said posts in-

termediate said base and ring for supporting the intermediate outer truss hoops of the hamper, substantially as and for the purpose specified. ¹⁰

In testimony whereof I have affixed my signature.

OSCAR L. BARTLETT.
